UNITED STATES PATENT OFFICE.

THEODORE MILLER, OF NEW YORK, N. Y.

MANICURING IMPLEMENT.

1,178,815.

Specification of Letters Patent.

Patented Apr. 11, 1916.

Application filed May 22, 1909. Serial No. 497,790.

To all whom it may concern:

Be it known that I, THEODORE MILLER, residing at New York, in the county of New York and State of New York, have invented 5 certain new and useful Improvements in Manicuring Implements, of which the following is a specification.

This invention relates broadly to manicuring implements and more particularly to 10 an implement adapted to hold a member which is employed to remove the surplus cuticle about the root or matrix of the finger nails.

The present invention contemplates cer- 15 tain improvements over that disclosed in my co-pending application Serial No. 453,957, filed September 21st, 1908.

One of the objects of the invention is to provide a new and improved implement 20 adapted to securely clamp a small cylindrical body of leather or other material which is employed in removing the surplus cuticle.

Another object is to provide clamping means whereby the cylindrical piece may be 25 quickly removed from the holder when worn and a fresh one substituted.

A further object is to provide an imple- 30 ment of the above character which will be self-contained and capable of being conveniently carried in the pocket.

Other objects will be in part obvious and in part pointed out hereinafter.

The invention accordingly consists in the features of construction, combinations of 35 elements and arrangements of parts hereinafter described, and the scope of the application of which will be indicated in the appended claims.

In the accompanying drawings wherein I 40 have illustrated a preferred form of the invention; Figure 1 is a view in elevation thereof; Fig. 2 is a longitudinal sectional view of the same; Fig. 3 is a similar view of a portion of the instrument showing the 45 manner in which the clamping means may be manipulated; Fig. 4 is a similar view showing the manner in which the clamping member may be inserted in the handle when the instrument is not in use; Fig. 5 is a view 50 in elevation showing a cartridge which is adapted to be carried in the handle of the instrument; Fig. 6 is a longitudinal sectional view of the holder showing the means em- 55 ployed for preventing the clamping member from being entirely withdrawn from the holder.

Similar reference characters refer to similar parts throughout the several views of the drawing.

Referring now to the drawings, 1 designates the handle of the instrument which, in the present instance, is hollow and closed at one end; the opposite end being open as shown so as to receive the holder 2. Holder 2 is adapted to be reversibly inserted in the 60 open end of the handle, as will be obvious from an inspection of the drawings.

3 indicates a substantially U shaped clamping member which is received in a central bore 4 of the holder 2, and is slidable 70 therein. This clamping member which is preferably made of spring metal has divergent opposed arms 5 which extend through a cap 6 inserted in the outer end of the holder, the construction being such that 75 when the member is pushed inward as shown in Fig. 2, arms 5 will be caused to approach each other and thereby clamp the cylindrical piece, and when withdrawn, as shown in Fig. 3, the arms will automatically separate. 80

In order to prevent the clamping member from being entirely withdrawn from the holder, a keeper 7 is inserted between the arms 5 within the holder. This keeper which is substantially T shape, as shown, is loosely 85 confined within the holder, the stem thereof extending within bore 4 and the cross piece or head being received in an enlarged portion 8 of said bore. It will be seen that when the clamping member is pulled outwardly from the holder, the inner end of the stem of the T-shaped keeper will be engaged by the end wall of the U-shaped clamping member, and that the opposite ends of the head of the keeper will engage the inner 90 annular edge of the cap 6 and positively prevent withdrawal of the clamping member beyond a prescribed limit.

The T-shaped keeper has peculiar advantages; its stem projecting into the reduced 100 rear portion of the bore 4 serves to retain a desirable length of the inner end of the clamping member within said bore for co-operating with the walls of the cap 6 to hold the clamping member relatively steady, even 105 when said clamping member is in its outermost position. The head part of the keeper fits loosely within the enlarged portion 8 of the bore 4 and engages the rear annular surface of the cap 6 for preventing outward 110 movement of the keeper, and engages the forward surface of the shoulder, formed by

the change in bore, for preventing rearward movement of the keeper.

The keeper, and also the clamping member 3, may be removed by detaching the cap 6, the presence of which in the bore 8, it will be noted, co-operates to transform said bore into an annular groove in which the head of the keeper plays. The keeper, being thus held relatively stationary and being between the arms of the clamping member, is engaged, upon its opposite side faces by said arms, and the friction set up by such engagement increases as the clamping member is forced inwardly. In forcing the clamping member inwardly, the outer surfaces of the arms engage the opposing faces of the cap 6, and the arms are forced toward each other and against the sides of the keeper.

The elongated friction surface provided by the stem of the keeper provides ample resistance to prevent accidental withdrawal of the clamping member. The keeper thus acts as effective means for retaining the clamping member in its inner or clamping position.

The engagement of the keeper or friction member 7 in the groove 8 obviously permits a limited lateral movement of the keeper with the jaws, and this is of especial value where an excess of pressure may be developed in one of the jaws over the other, as will constantly occur in practice, in that it permits the keeper to transmit the excessive pressure to the second jaw and force the second jaw tightly against the wall of the bore 4 so as to retain the second jaw against a natural tendency to creep outwardly from the holder.

9 indicates a cartridge which is adapted to be received within the handle of the instrument. This cartridge comprises receptacles 10 and 11, the larger of which is adapted to carry the cylindrical pieces to be used in manicuring and the smaller receptacle is intended to be used for a manicuring abradant in paste form. Receptacle 11 is provided with a reduced portion which fits within receptacle 10 and forms a closure therefor.

50 Having thus described my invention the manner in which the same can be used may now be understood. The holder is first withdrawn from the handle which permits the cartridge to be withdrawn therefrom.

55 The holder is then re-inserted in the handle in the manner shown in Fig. 2 of the drawings. The clamping member 3 may then be pulled outwardly to permit a cylindrical piece to be inserted between the ends thereof so that when said clamping member is pushed inwardly within the holder, the arms will approach each other and firmly clamp such cylindrical piece. The instrument is then ready for use and may be grasped in 65 the hand in a manner similar to that in

which a pencil is grasped and the cylindrical piece reciprocated with respect to the edge of the cuticle of the nail.

It will accordingly be seen that I have provided a simply constructed implement of the above character which is not only self-contained but is capable of being conveniently carried about in the pocket. It may also be manufactured at a modicum of cost.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

Having described my invention, what I claim as new and desire to secure by Letters Patent is:

1. In a manicuring implement, a pair of flexible jaws, an operating member slidable longitudinally over said jaws to close said jaws, and tending to flex a portion of said jaws, and means for limiting the movement of said jaws, said means being carried by said operating member and frictionally engaging said jaws and thereby serving also to frictionally retard the movement of said operating member relatively to said jaws.

2. In a manicuring implement, a pair of jaws, movable squeezing means engaging said jaws for squeezing said jaws toward each other, and a friction member movable with said squeezing means disposed between opposing surfaces of said jaws having frictional engagement therewith to retard movement of said squeezing means from squeezing position.

3. In a manicuring implement, a pair of jaws, movable squeezing means engaging said jaws to squeeze said jaws toward each other, a T-shaped friction member disposed with its stem portion extending longitudinally between said jaws to provide a considerable surface frictionally engaged by the opposing inner surfaces of said jaws, the opposite end portions of the head of said T-shaped friction member projecting outwardly from between said jaws at opposite sides thereof, and means engaging the projecting portions of the head of said T-shaped friction member to move said T-shaped friction member with said squeezing means, whereby to retard movement of said squeezing means from squeezing position.

4. In a manicuring implement, a pair of jaws, movable squeezing means engaging said jaws to squeeze said jaws toward each other, an elongated friction member extending longitudinally between the opposing surfaces of said jaws having opposite surface portions frictionally engaged by the op-
